UNITED STATES PATENT OFFICE.

JOSEPH H. EWING, OF MALTA, OHIO.

GAMING DEVICE.

Application filed March 7, 1923. Serial No. 623,442.

To all whom it may concern:

Be it known that I, JOSEPH H. EWING, a citizen of the United States of America, residing at Malta, in the county of Morgan and State of Ohio, have invented new and useful Improvements in Gaming Devices, of which the following is a specification.

The object of the invention is to provide a device adapted to be used for the entertainment, amusement and test of skill of the participants in the act of rolling, cuing or otherwise manipulating spherical playing objects such as marbles or balls. A further object is to provide in such a device a playing board adapted to be supported at an inclination with means for varying the angle of inclination from the horizontal.

With these objects in view the invention consists in a construction and combination of parts of which a preferred embodiment is shown in the accompanying drawings, wherein:

Figure 1 is a side elevational view of the invention.

Figure 2 is a plan view.

Figure 3 is a section on the line 3-3 of Figure 2.

Figure 4 is a section on the line 4-4 of Figure 2.

The device consists of a base 1 consisting of a board designed to rest at one end upon a table or other supporting surface and provided at the other end with adjustable legs 2 which consist preferably of pipe sections 3 threaded at one end for a substantial portion of the length of the leg for engagement with a waste nut 4 which is secured on the under surface of the base 1, the leg being provided at the opposite end with a pipe cap 5 constituting the foot. The pipe section being threadingly engaged with the waste nut, the legs may be rotated and by means of the screw connection their extent from the base will be varied and thus the angular disposition of the base may be adjusted within the limits provided by the size legs used. The upper face of the base constitutes the playing surface and is bounded on the edges by upstanding walls 6, the longitudinal sections of these walls constituting the outer walls of alleys 7 of which the inner walls 8 are arranged in parallelism with the outer walls. The two alleys are thus dis-

posed at opposite sides of the base and inter-communicate by means of an arcuate or semi-circular alley 9 of which the walls are in continuation of the walls of the alleys 7. From the lower or inner arcuate wall of the alley 9 the radial plates 10 project but terminate short of the outer arcuate wall of the 60 alley to provide a free space for the traverse of playing objects 11 which may be impelled or manipulated by the fingers or with a cue or with a mallet, whatever the players may elect. The radial plates 10 define respectively a center pocket 12 laterally accessible from the alley 10 and outer pockets 13 on either side of the pocket 12 and still other pockets 14 of much greater width than the pockets 13 or 12. The playing object 11 70 may be started from the bottom of either alley 7 and driven around the communicating alley 9, the purpose being to dispose it in one of the pockets 12, 13 or 14. Obviously it requires greater skill to drop the object 75 in the center pocket 12 than in any of the other pockets and less skill to deposit it in one of the pockets 13 than in the pockets 12 but greater skill to deposit it in the pockets 13 than in the pockets 14. In playing the 80 game an arbitrary number of points may be assigned to each pocket with the center pocket obviously varied or having the value of the greatest number of points. Since passage through the arcuate alley 9 by the 85 pockets 14, 13 and 12 is restricted substantially to the diameter of the playing object, it is essential that the latter follow the outer arcuate wall of the arcuate alley and thus it is incumbent on the player to impact or impel the playing object with just the sufficient force to drop it in the desired pocket.

Having described the invention, what is claimed as new and useful is:

A device for the purpose indicated comprising parallel alleys and a communicating arcuate alley, and radial plates disposed in the arcuate alley and defining pockets between them, said plates having a radial extent just sufficient to permit the passage of a 100 spherical playing object between them and the outer wall of the arcuate alley.

In testimony whereof he affixes his signature.

JOSEPH H. EWING.
